UNITED STATES PATENT OFFICE.

JOSEPH G. WILLIAMS, OF NEW YORK, N. Y., ASSIGNOR, BY DIRECT AND MESNE ASSIGNMENTS, TO THE CURRENT-SAVING ELECTRIC SIGN COMPANY, INC., OF NEW YORK, N. Y., A CORPORATION OF NEW YORK.

ILLUMINATED SIGN.

1,279,197,

Specification of Letters Patent. Patented Sept. 17, 1918.

Application filed May 20, 1914. Serial No. 839,820.

To all whom it may concern:

Be it known that I, JOSEPH G. WILLIAMS, a citizen of the U. S. of America, residing at New York, in the county of New York and State of New York, have invented new and useful Improvements in Illuminated Signs, of which the following is a specification.

This invention relates to that class of signs having characters so constructed as to be visible in daylight to the eye, and further constructed to support a number of incandescent lamps arranged in position to illuminate the characters of a sign and be visible therewith at night. This type of sign is commonly termed a "live light" sign by reason of the fact that the incandescent lamps are visible with the characters which they illuminate.

Illuminated signs as at present constructed have characters of the sunken trough, or the extension trough type, or characters of the flush type. In live light signs provided with the sunken or the extension trough characters it has heretofore been the practice to arrange the incandescent lamps so as to extend outwardly from the sign or in directions at right angles to the bottom or back surface of the characters. In instances where the sign had characters on its opposite faces or conformed to what is generally known as a double faced sign, the arrangement of attaching the incandescent lamps to the bottoms or backs of the characters made necessary the employment of a separate bank or battery of lamps for each of the characters on the opposite faces of the sign. This was made necessary by reason of the fact that the said bottoms or backs of the characters were formed of metal or other analogous material impervious to the action of light. Thus it is obvious that in a double faced sign the above stated arrangement of the lamps made the cost of upkeep of such sign, by reason of the great amount of current needed for the lamps, equal to twice that required with a sign having characters on one face only. This, of course, does not take into consideration the item of upkeep incidental to the replacing of burned-out lamps nor the initial cost of the sign. It will be further observed that with the arrangement of lamps in a trough character as previously pointed out, but a comparatively

small amount of light passes directly outward from the characters. Such small amount comes from the end of the incandescent filament, while the light from the long sides of the filament is directed onto the surrounding side walls of the trough characters and is then reflected outwardly by the surfaces of these side walls which are invariably painted white or with a light color.

Now from the foregoing it will be obvious that ample room exists for improvement in the arrangement of the illuminating agents in a single or double faced live light sign, and for improvements tending to reduce the initial cost and the cost of maintenance of a double faced live light sign.

With this in view the general object of the present invention is to obtain maximum illuminating efficiency from the incandescent lamps of a live light sign of single or of double faced construction, and to effect the illumination of the registering portions of opposite characters in a double faced sign simultaneously with a single battery or bank of incandescent lamps.

And to these ends the invention resides in incorporating in the frame or casing of a sign a translucent reflecting plate provided at chosen intervals with transparent openings arranged in such relation as to define a required character or characters, arranging incandescent lamps in alinement with the light openings of the plate and further in so arranging the said lamps that lines drawn from their tips to their bases will be in planes parallel with the surface of the plate.

Other objects will appear and be better understood from that embodiment of my invention of which the following is a specification, reference being had to the accompanying drawings forming part hereof, in which:

Figure 1 is a view in front elevation of a sign constructed in accordance with the present invention.

Fig. 2 is a view in edge elevation thereof.

Fig. 3 is a rear elevation of the sign.

Fig. 4 is a rear elevation with the back plate removed.

Fig. 5 is a vertical central sectional view through the sign.

Fig. 6 is a rear elevation of a modified construction of sign.

Fig. 7 is a view in edge elevation thereof.

In Figs. 1 to 5 inclusive, I have shown the invention used in connection with a sign one of whose sides is comprised of sunken characters and the other of whose sides is made up of extension characters. In Figs. 6 and 7 the invention is shown in connection with a sign one of whose sides consists of sunken characters and the other of whose sides consists of flush characters. At the outset it 10 may be stated that this showing is simply illustrative, and from what will hereinafter appear it can be readily seen how my invention may be applied to a sign, the characters on one side of which conform in construction 15 to those on the other, or in which combinations of constructions different from those shown, are used. In Figs. 1 to 5 inclusive, 1 indicates generally the body of the sign which may be of the usual or any approved 20 construction. What will subsequently be termed the opposite faces of this body, are indicated respectively, by 2 and 3. The face 2 is herein shown as being provided with a series of characters of the sunken type, and 25 the side 3 carries a series of characters of the extension type. Since the general characteristics of these types of characters are old and well-known to the trade, a detailed description is deemed as unnecessary except 30 as for the background or bottom wall.

Heretofore, it has been customary to form this background or bottom wall of metal or other like substance impervious to light substance and to provide the said wall with the 35 usual electric sockets for the incandescent lamps. In the present instance this background or bottom wall which is indicated by the numeral 5, forms a bottom common to opposite characters on faces 2 and 3, and is 40 constructed so as to permit the light of the lamps to illuminate simultaneously registering parts of the alining characters on opposite faces of the sign. In appearance this wall is a relatively thin plate, a portion or 45 portions of which are so constructed as to permit the passage therethrough of light. These light transmitting portions are arranged suitable distances apart and when the plate is arranged in the body of a double 50 faced sign, the said light transmitting portions will be in alinement with the registering portions of opposite alining characters, so that an incandescent lamp arranged so as to extend parallel with the surface of one face 55 of the plate, and further, arranged in alinement with the light transmitting portions, will be visible from either face of the sign. Now in so far as the principle of the present invention is concerned, it is immaterial as 60 to the substance of which the plate is formed or as to the color of the plate, since the underlying principle of that part of the invention now under discussion, resides in illuminating the registering portions of alining 65 characters of a double faced live light sign,

simultaneously. A preferred construction of plate is shown in the drawings. In this case the plate is formed of glass ground or otherwise suitably treated so as to render it translucent and provided at chosen intervals with 70 transparent portions 10. It will be noted by reference to Figs. 3 and 6 that the transparent portions 10 are arranged so as to define the characters which go to make up the term of the sign. With this construction and 75 when the lamps are placed in alinement with the transparent portions 10, the effect had on viewing the character on the side 3 of the sign is the same as in observing a character of approximately twice the depth of the 80 character on side 3, and in the instance of a flush character as shown in Fig. 6, the effect is to give this flush character the semblance of a sunken or trough character. This illusion is undoubtedly due to the light 85 rays coming through the transparent portions 10, being of greater intensity than those coming through the translucent parts of the bottom plate 5 which intervene and surround the transparent portions. 90

The remaining feature of novelty in my invention resides in the disposition of the lamps 8. Referring now to the drawings it will be observed that the sockets 7 for these lamps are arranged on the side walls of the 9 troughs rather than on the bottom plate or background, as has heretofore been the practice and as hereinbefore mentioned. The sockets are connected in the usual manner to the feed wires 9 which are in turn connected in the usual manner with a source of electric energy. By so disposing the sockets it will be observed that when the bulbs or lamps 8 are attached thereto in the ordinary manner, the said bulbs will be parallel, or substantially so, with the adjacent surface of reflecting plate 5 so that when the filaments in the bulbs are in an incandescent state, the major volume of the light will issue directly outward from the character rather than indirectly or by reflection, as is the case when the direction of extension of the filaments is in planes at right angles to that shown. Thus it will be seen that with this construction maximum intensity of illumination of the character is had with an amount of electric energy far less than would be required by carrying out the old arrangement hereinbefore stated. The lamps or bulbs 8 and the transparent portions 10 are arranged in such relation as to aline one with the other, so that bulbs arranged in the trough on side 2 will be visible from side 3 through the transparent portions 10. 1

In instances where the same term is had on the opposite sides of a sign and the outlines or opposite characters of such term register one with the other as would be the case of the sign having on opposite faces the term shown in Fig. 6, then a single bank or bat-

teries of lamps is all that is necessary to illuminate any two opposite characters. In instances where characters whose outlines do not register when superimposed one upon the other, are arranged opposite to each other to make up for instance, the term shown on the opposite sides of the sign in Figs. 1 to 5, then additional lamps must be employed in those characters which depend in part on the light coming through the transparent or translucent portions 10, for their illumination. In such instances as will be observed by referring to Figs. 1 and 3, separate sets of lamps are employed to illuminate those portions of the characters on side 3 which do not register or aline with any part of opposite characters on side 2. In carrying out this arrangement the lamps are disposed in the body 1, and arranged as shown by dotted lines in Fig. 1 and between the background or reflecting plate 5 and the side 2. In this instance it will, of course, be understood that suitable supports are provided for the lamp sockets and that transparent portions 10 will be had in the plate 5 and in alinement with these sets of lamps. What has been said with reference to illuminating non-symmetrical characters disposed on opposite sides of a sign, such as shown in Figs. 1 and 3, may be taken to apply to the combination of characters on opposite sides of the forms shown in Figs. 6 and 7, and in fact, to all other single constructions and combinations of constructions of characters now in use, or to which the principles of this invention may apply.

It will be obvious to those skilled in the art that the arrangement of the lamps and the plate 5, may be used with any of the conventional-types of sign characters now in use.

What is claimed as new is:

1. In a live light electric sign, the combination of a frame, a translucent plate connected to and extending parallel with the said frame, said plate having a plurality of transparent portions arranged in such relation to each other as to define a desired sign character, and a plurality of incandescent lamps connected to the frame and arranged in alinement with the transparent portions of the said plate.

2. A double faced electric sign including a body with open sided frame constructions which form alining characters on the opposite sides thereof, a reflecting plate connected to the body and interposed between opposite characters and having transparent portions in alinement with the registering

portions of the opposite characters, and a set of incandescent lamps connected to the body and disposed in alinement with the said transparent portions.

3. A double faced electric sign including a body with open sided frame structures which form sign characters in one face thereof, and open sided frame structures forming sunken characters in the opposite face thereof and alining with the first-named characters, a plate interposed between opposite characters and connected to the body, said plate having transparent portions and incandescent lamps connected to the body and disposed in alinement with said transparent portions, and arranged so that lines drawn from their tips to their bases will extend in planes parallel with the adjacent surface of said plate.

4. A double faced electric sign including a body with open sided frame structures which form sunken characters on one face of the sign and extension characters on the opposite face of the sign and in alinement with the first named characters, a plate connected to the body and interposed between the said characters and having transparent portions in alinement with the registering portions of said opposite characters, and incandescent lamps connected to a side wall of the sunken characters and arranged in alinement with the transparent portions of the plate.

5. A sign comprising a hollow body having oppositely disposed hollow characters a plate of translucent material interposed between said characters and having a transparent portion disposed in alinement with the alining portions of said characters, and an incandescent lamp connected to the body and disposed in alinement with the transparent portion of said plate.

6. A sign comprising a hollow body having oppositely disposed hollow characters a plate of translucent material interposed between said characters and having a plurality of spaced transparent portions disposed in alinement with the opposite alining portion of said characters and a plurality of incandescent lamps connected to the body and disposed in alinement with the transparent portions of the said plates.

In testimony whereof I affix my signature in presence of two witnesses.
